UNITED STATES PATENT OFFICE.

ALFRED SEELEY, OF ROCHDALE, ENGLAND.

MACHINERY FOR USE IN DYEING AND ANALOGOUS PURPOSES.

1,249,677.

Specification of Letters Patent. Patented Dec. 11, 1917.

Application filed March 16, 1916. Serial No. 84,609.

To all whom it may concern:

Be it known that I, ALFRED SEELEY, a subject of the King of the United Kingdom of Great Britain and Ireland, and resident of 5 Melrose House, Bentmeadows, Rochdale, in the county of Lancaster, England, have invented new and useful Improvements in Machinery for Use in Dyeing and Analogous Purposes, of which the following is a specification.

This invention relates to machinery for use in dyeing and analogous processes and consists in machines which facilitate the dyeing and sizing of small warps or like assemblages of yarns or threads and other analogous processes and enable waste of dyes, size and other materials and other inconveniences heretofore experienced largely to be obviated and are simple and compact in 20 construction and convenient in use.

For convenience this invention will be described as exemplified in a machine for dyeing small warps.

In a machine provided according to this 25 invention, a trough or tank to contain dye is provided and a roller, cylinder, drum or barrel is provided and immersed in or made to dip into the dye so that a warp may be passed once or any suitable number of times 30 around the roller, cylinder, drum or barrel and in passing around it be dipped into the dye in the trough or tank. In order that the warp may be passed around the roller, cylinder, drum or barrel without one part 35 of such warp being rubbed against another a guide or guides, or an auxiliary roller placed obliquely is or are provided.

Provision is preferably made for the cylinder, drum or barrel to be made to revolve 40 sometimes in one direction and sometimes in the opposite direction as for example by the use of reversible driving gear or a pulley driven sometimes by an open and sometimes by a crossed belt so that a warp passed 45 around the roller, cylinder, drum or barrel may be passed through the liquid in the trough or tank first in one direction and then in the opposite once or oftener as may be desirable in order to insure equal dyeing 50 throughout its length.

A pair or group or pairs or groups of squeezing rollers mounted and worked in any position and manner convenient is or are provided to squeeze a warp after it 55 leaves the roller, cylinder, drum or barrel.

If desirable there may be a squeezing roller or squeezing rollers to press or squeeze a warp before it passes on to the roller, cylinder, drum or barrel. Provision may be made for the liquid in the trough or tank of 60 a machine provided according to this invention to be changed from time to time as may be desirable for different dyeing or other processes to be accomplished.

One form of machine constructed according to this invention is illustrated by way of example in the accompanying drawings in which Figure 1 is an end elevation of the machine with some parts at one end removed showing some parts in section and Fig. 2 is 70 a plan, the lines A A of Fig. 2 indicating the plane on which the section in Fig. 1 is taken.

The same letters and numerals of reference are employed to indicate corresponding 75 parts in both of the figures.

In the drawings, *a* is a tank to contain dye having, in the lower part of its interior, brackets *b* secured upon its end *c* *c'* and provided with bearings in which is mounted the 80 axle *d* of a barrel *e* formed of staves mounted around disks *f* secured upon the axle *d*. The ends *c* *c'* of the tank *a* are provided with brackets *g* in which are mounted swivel bearings *h* mounted to be oscillated about 85 vertical axes. In the swivel bearings *h* an auxiliary or guide roller *i* is mounted, so that it can be revolved but can not be moved lengthwise. The brackets *g* are secured to the ends *c* *c'* of the tank *a* in such position 90 that the roller *i* is oblique to the barrel *e* in such a way that a warp led from a fixed position near one end of the tank *a* and passed around and around the barrel *e* and roller *i* alternately to another fixed position near the other end of the tank *a* will 95 pass around the barrel *e* when it is revolved without one part of the warp rubbing against another. The swivel bearings *h* enable the brackets *g* easily to be adjusted into 100 and fixed in proper position without risk of the projecting axles of the roller *i* binding in their bearings and enable like parts to be used with tanks of different lengths in different machines.

The axle *d* is provided with a chain-wheel *j* around which passes a chain *k* passing around another chain wheel *l* fast with a toothed wheel *m* mounted revolvably upon a stud *n* secured to the end *c'* of the tank *a*. The 110

toothed wheel m is in gear with a toothed wheel o mounted fast upon a shaft p mounted revolubly in bearings in brackets q secured upon the one side t of the tank a . Fast upon the shaft p are mounted a chain-wheel u and a roller v . A bevel wheel w and a cone pulley x with a bevel wheel y fast to it are mounted loose upon the shaft p but held against movement lengthwise of the shaft p . A bevel wheel z in gear with both of the bevel wheels w y is mounted so that it can be revolved upon a stud carried by a bracket 1 secured to the side t of the tank a . A clutch collar with clutch teeth adapted to engage corresponding teeth upon the bevel wheels w y is mounted upon the shaft p and in engagement therewith by means of a key and groove or the like so that it may be moved lengthwise of the shaft p either into engagement with either of the bevel wheels w y or be placed between them in the position in which it is indicated in Fig. 2 disengaged from both so that motion imparted to the cone pulley x in one direction may be made to drive the shaft p in the like direction by means of the clutch collar 2 or in the opposite direction by means of the bevel wheels y z w or to leave it unturned. A hand lever 3 mounted to be oscillated about a stud 4 secured to the side t of the tank a is provided with a stud in engagement with a groove formed in the clutch collar 2 so that the hand lever 3 may be used to move the clutch collar 2 into engagement with either of the bevels w y or to disengage it from both. Around the chain-wheel u is passed a chain 5 passed also around a chain-wheel 6 fast upon a shaft 7 which has a roller v fast upon it and is mounted to be revolved in bearings in brackets q secured upon the side t of the tank a . The brackets q are provided with slots 9 in their upper part and in each pair of brackets q is mounted a roller 10 the axle of which at each end enters and is guided in the slot 9 of one of the brackets q and is engaged with one of two links 11 connected by studs 12 to arms of a pair of hand levers 13 fast upon a shaft 14 which is mounted to be oscillated in bearings in brackets 15 secured upon the upper ends of the pair of brackets q . Each hand lever 13 is furnished with a weight 16. Each pair of hand levers 13 may be turned into the position in which it is indicated in the drawings 55 for the weights 16 thereon to press down the roller 10 with which it is used toward the roller v between the brackets q of the pair in which such roller 10 is mounted or may be turned so that the said roller 10 is raised 60 and held away from the roller v . The links 11 are shaped so as to allow the studs 12 to be turned from the positions in which they are indicated in the drawings to the positions beyond the vertical planes passing through the axes of the shafts 14 by which

they are carried respectively. Between the brackets q in each pair is an inclined plate 17 to lead into the tank a liquid which may fall from the roller v or a warp squeezed against it by the roller 10 used with it. The plate 17 may be formed separately and secured in position in any convenient way or may be formed in one with either or both of the brackets q with which it is to be used. 70 18 are blocks provided in the bottom of the interior of the tank a at the sides to support T pieces 19 from each of which two pipes 20 extend in opposite directions toward the ends c c' of the tank a . The T pieces 19 are secured on the lower ends of vertical pipes 80 21 connected by unions to the lower ends of branch pipes 22 partly curved, which are connected by a T piece to a pipe 23 provided with a tap 24 and serving for the supply of steam for heating liquid in the tank a . The 85 bottom of the tank a is furnished with an outlet pipe 25 having a tap 26 and enabling liquid to be run off from the tank a when it is to be emptied. 90 In the use of the machine the tank a is filled with dye liquor of any kind to a depth sufficient to immerse part or the whole of the barrel e or to a greater depth as may be desirable in any case, for example to the level indicated by the line E, and the liquor is 95 kept heated if need be as in the ordinary way of dyeing by steam passed into it through the pipes 23, 22, 21 and 20. The warp to be dyed is led between the one roller v and the one roller 10 used with it, the roller 10 being raised from the roller v to allow the warp to be passed beneath it and passed a suitable number of times around the barrel e and the roller i in the manner indicated by lines F, and then between the 100 other roller v and the roller 10 used with it, the roller 10 being raised to allow the warp to be passed beneath it. Ordinarily, much as in dyeing warps in the machines heretofore used, a warp to be dyed is led around the barrel e and roller i by being attached to the end of a tape or the like led around the barrel e and roller i in readiness, usually by being attached to the end of a warp being withdrawn from the machine as it is about 110 to pass to the roller v over which it passes to the barrel e . Then the rollers 10 are lowered to press the warp against the rollers v beneath them. Then the cone pulley x being in motion the clutch collar 2 is moved 120 to place the cone pulley x into connection with the corresponding teeth of the bevel wheel w or the bevel wheel y according as the warp is required to pass first around the barrel e and roller i in a clockwise or counter clockwise direction as seen in Fig. 1, so that the shaft p being made to revolve will cause the warp to be delivered to the barrel e by the one pair of rollers v^{10} and to be 125 passed around the barrel e and roller i by 130

the revolution of the barrel *e* and to be drawn from the barrel *e* by the other pair of rollers *v*¹⁰. The warp after leaving the barrel *e* is pressed between the roller *v* and the roller 10 drawing it from the barrel so that much of the liquid carried by the warp from the tank *a* is squeezed out and flows down the plate 17 below back into the tank *a*. The warp delivered by the rollers *v*¹⁰ drawing it from the barrel *e* may be allowed to pass into any suitable receptacle. When the movement of the warp around the barrel *e* and the roller *i* in one direction has continued so long that the end of the warp arrives near the roller *v* over which it is passing to the barrel *e* the clutch collar 2 is moved out of engagement with the one of the bevel wheels *y*, *w* and into engagement with the other so that the directions of the revolution of the shaft *p* and barrel *e* and rollers *v* are reversed and the warp is drawn through the liquid in the tank *a* in the opposite direction until the beginning of the warp is brought again near the one roller *v* and then either the warp may be withdrawn from the tank *a* by being unwound from the barrel by the rollers *v*¹⁰ then acting upon it or if desirable the clutch collar may be moved again to reverse the direction of the shaft *p* in order that the warp may be drawn through the liquid in the tank *a* and so on as often as may be necessary. When one warp is to be withdrawn from the barrel *e* and roller *i*, another may be attached to its end so as to be led around the barrel *e* and roller *i* in the withdrawal of the first.

If desirable after a warp has been led through one liquor in its passage around the barrel *e* once or oftener the liquor in the tank *a* may be run off and another liquid be run in and the warp be passed in opposite directions through that liquid as through the former.

Ordinarily only the roller 10 under which the warp passes from the barrel *e* is required to press upon the warp to squeeze liquid therefrom, and the roller 10 under which the warp passes to the barrel *e* is lifted from the warp and the rollers 10 are lowered in turn to press upon the warp when the clutch-collar 2 is to be moved to reverse the direction of the revolution of the barrel *e*.

The time during which a warp is to be dipped in the liquid in the tank *a* at each passage may be controlled by the use of one or other of the steps of the cone pulley *x* in the transmission of motion to the barrel *e* and if desirable also by the use of any other means for changing the speed of the barrel *e* and as further means of regulating the time for which each part of a warp is to be dipped in the liquid in the tank *a* the warp may be led once or as many times around the barrel *e* and roller *i* as may be desirable and the warp may be passed around the barrel

e a greater or less number of times as may be desirable in any case. Ordinarily to insure equal dyeing from end to end of a warp the warp is made to pass around the barrel *e* equally often in each direction. 70

Two or more barrels *e* may be provided in a machine if desirable and may be used with one oblique roller *i* or more as may be convenient in any case.

If desirable in any case a barrel *e* may be arranged always to be revolved only in one direction and in any such case the two ends of a warp may be fastened together so that the warp may be passed as often as may be requisite through the liquid in the tank *a* in 80 which such barrel is mounted.

Machines provided according to this invention are intended specially for use in dyeing and sizing small warps and like assemblages of yarn or thread and obviate the 85 waste of dyes and size and the inconveniences involved in dyeing and sizing small warps and like assemblages of yarn or thread but may be used or adapted for subjecting small warps and like assemblages of 90 yarn or thread to treatment by steam or liquids or gases or combinations thereof instead of or in addition to dye and size.

The machine illustrated in the accompanying drawings can be used for sizing but 95 if so used would advantageously be provided with devices similar to those used in sizing machines in ordinary use for maintaining the level of the size approximately constant in the tank. 100

Machines provided according to this invention may be used or adapted also for other operations as for example, dyeing, sizing or applying liquids or gases for other purposes to warps in tape form or linked 105 warps or woven fabrics or yarn in hanks fastened together or otherwise adapted to be passed in series through the machines.

What I do claim as my invention and desire to secure by Letters Patent is:— 110

1. A machine for dyeing or sizing warps or like assemblages of yarns or threads or other analogous process as hereinbefore described comprising a vessel to contain liquid, revoluble immersing means mounted in such vessel to be in liquid therein, means for revolving such immersing means and means for guiding material to and from such immersing means and means oblique to the said immersing means for guiding material 115 to and from such immersing means and preventing one part of such material from rubbing against another, substantially as hereinbefore described.

2. A machine for dyeing or sizing warps 120 or like assemblages of yarns or threads or other analogous process as hereinbefore described comprising a vessel to contain liquid, revoluble immersing means mounted in such vessel to be in liquid therein, means for re- 130

volving such immersing means, and revol-
uble guiding means oblique to such immers-
ing means for guiding material to and from
such immersing means and keeping one part
5 of such material from rubbing against
another, substantially as hereinbefore de-
scribed.

3. A machine for dyeing or sizing warps
or like assemblages of yarns or threads or
10 other analogous process as hereinbefore de-
scribed, comprising a vessel to contain
liquid, revoluble immersing means mounted
in such vessel to be in liquid therein, means
for revolving such immersing means, means
15 oblique to said immersing means for guid-
ing material to and from such immersing
means and preventing one part of such ma-
terial from rubbing against another and
squeezing means for squeezing material on
20 the way to or from the immersing means,
substantially as hereinbefore described.

4. A machine for dyeing or sizing warps
or like assemblages of yarns or threads or
25 other analogous process as hereinbefore de-
scribed comprising a vessel to contain liquid,
revoluble immersing means mounted in such
vessel to be in liquid therein, means for re-
volving such immersing means, means for
30 reversing the direction of revolution of such
immersing means, means oblique to said im-
mersing means, for guiding material to and
from such immersing means and prevent-
ing one part of such material from rubbing
35 against another, and squeezing means in two
sets for squeezing material on the way from
the immersing means, substantially as herein-
before described.

5. A machine for dyeing or sizing warps
or like assemblages of yarns or threads or
40 other analogous process as hereinbefore de-
scribed comprising a vessel to contain liquid,
revoluble immersing means mounted in such
vessel to be in liquid therein, means for re-
volving such immersing means, revoluble
45 guiding means oblique to such immersing
means for guiding material to and from
such immersing means and keeping one part
of such material from rubbing against an-
other and squeezing means for squeezing
50 material on the way from the immersing
means, substantially as hereinbefore de-
scribed.

6. A machine for dyeing or sizing warps
or like assemblages of yarns or threads or
55 other analogous process as hereinbefore de-
scribed comprising a vessel to contain liquid,
revoluble immersing means mounted in such
vessel to be in liquid therein, means for re-
volving such immersing means, means for
60 reversing the direction of revolution of such
immersing means, revoluble guiding means
oblique to such immersing means for guid-
ing material to and from such immersing
means and squeezing means in two sets for
65 squeezing material on the way from the im-

mersing means substantially as hereinbefore
described.

7. A machine for dyeing or sizing warps
or like assemblages of yarns or threads or
70 other analogous process as hereinbefore de-
scribed comprising a vessel to contain liquid,
a revoluble barrel mounted in such vessel
to dip into liquid therein, means for revolv-
ing such barrel and means oblique to the
75 said immersing means, for guiding material
to and from such barrel and preventing one
part of such material from rubbing against
another, substantially as hereinbefore de-
scribed.

8. A machine for dyeing or sizing warps
or like assemblages of yarns or threads or
80 other analogous process as hereinbefore de-
scribed, comprising a vessel to contain liquid,
a revoluble barrel mounted in such vessel to
dip into liquid therein, means for revolving
such barrel and a revoluble guide roller
85 mounted in the said vessel obliquely to the
barrel for guiding material to and from
such barrel, substantially as hereinbefore
described.

9. A machine for dyeing or sizing warps
or like assemblages of yarns or threads or
other analogous process as hereinbefore de-
scribed comprising a vessel to contain liquid,
a revoluble barrel mounted in such vessel
95 to dip into liquid therein, means for revolv-
ing such barrel, means oblique to said im-
mersing means for guiding material to and
from such barrel and preventing one part of
such material from rubbing against another
100 and squeezing rollers for squeezing material
on the way from such barrel, substantially
as hereinbefore described.

10. A machine for dyeing or sizing warps
or like assemblages of yarns or threads or
105 other analogous process as hereinbefore de-
scribed comprising a vessel to contain liquid,
a revoluble barrel mounted in such vessel to
dip into liquid therein, means for revolving
such barrel, means for reversing the direc-
110 tion of revolution of such barrel, means
oblique to said immersing means for guid-
ing material to and from such barrel and
preventing one part of such material from
rubbing against another and squeezing roll-
115 ers in two sets for squeezing material on the
way from such barrel, substantially as herein-
before described.

11. A machine for dyeing or sizing warps
or like assemblages of yarns or threads or
120 other analogous process as hereinbefore de-
scribed, comprising a vessel to contain liquid,
a revoluble barrel mounted in such vessel
to dip into liquid therein, means for revolv-
ing such barrel, a revoluble guide roller
125 mounted in the said vessel obliquely to the
barrel for guiding material to and from
such barrel, and squeezing rollers for squeez-
ing material on the way from such barrel,
substantially as hereinbefore described.

12. A machine for dyeing or sizing warps or like assemblages of yarns or threads or other analogous process as hereinbefore described, comprising a vessel to contain liquid, 5 a revoluble barrel mounted in such vessel to dip into liquid therein, means for revolving such barrel, means for reversing the direction of revolution of such barrel, a revoluble guide roller mounted in the said vessel obliquely to the barrel and squeezing 10 rollers in two sets for squeezing material on

the way from such barrel, substantially as hereinbefore described.

In testimony, that I claim the foregoing as my invention, I have signed my name in 15 presence of two witnesses, this second day of March 1916.

ALFRED SEELEY.
